United States Patent

Des. 235,732
Patented July 8, 1975

235,732

JUG

James E. Plummer, 2530 Beaufort, Toledo, Ohio 43613

Filed Oct. 1, 1973, Ser. No. 402,282

Term of patent 14 years

Int. Cl. D9—01

U.S. Cl. D9—39

FIG. 1

FIG. 3

FIG. 2

FIG. 5

FIG. 4

FIG. 1 is a front elevational view of a jug showing my new design, the opposite side being a mirror image of the side shown;

FIG. 2 is an elevational view taken from the left of FIG. 1;

FIG. 3 is an elevational view taken from the right of FIG. 1;

FIG. 4 is a top plan view thereof; and

FIG. 5 is a sectional view taken through lines 5—5 of FIG. 1.

I claim:

The ornamental design for a jug, substantially as shown and described.
